UNITED STATES PATENT OFFICE.

JOHN ANTON FEIERABEND, OF SWISSVALE, PENNSYLVANIA.

METAL FRAME FOR WINDOW-SCREENS.

1,171,184.

Specification of Letters Patent. Patented Feb. 8, 1916.

Application filed October 6, 1915. Serial No. 54,395.

To all whom it may concern:

Be it known that I, JOHN A. FEIERABEND, a citizen of the United States, residing at Swissvale, in the county of Allegheny and State of Pennsylvania, have invented certain new and useful Improvements in Metal Frames for Window-Screens, of which the following is a specification.

This invention relates to window screens and more particularly to that class of screens which is extensible, being composed of a plurality of sections.

An important object of this invention is the provision of a spring member for slidably holding the sections together.

Another object is to provide means for strengthening the corners and prevent their coming apart.

With these and other objects in view such as simplicity, cheapness in manufacture, durability and the general improvement of the art, the invention consists in the novel construction and arrangement of parts herein-after more fully described and claimed and illustrated in the accompanying drawings, in which:

Figure 1 is a view of my improved screen open its full width, Fig. 2 is a top plan view, Fig. 3 is an end view of the screen closed, Fig. 4 is a detail view partly in section, Fig. 5 is a fragmentary view of a side and a top strip showing the spring guide, Fig. 6 is a fragmentary view of one corner showing the strip retainer, and Fig. 7 is a sectional view on the line 7—7 of Fig. 4.

In the drawings in which like numerals indicate like parts in the several views, the numeral 1 designates the screen as a whole, and 2 and 3 designate the sections comprising the screen. These sections are identical in construction and consist of the frame 4, 5, 6 and 7 and mesh or screen wire 8. The parts 4, 5, 6 and 7 are bent upon themselves forming portions 9 and 10 between which the screen wire 8 is clamped. One end of each of the portions 10 of the parts 4 and 6 is cut as at 11 as shown in Fig. 5 to form spring guide members 12. The portions 9 of the parts 4 and 6 are inserted between the portions 9 and 10 of 7, and the portion 10 is inserted between the portions 9 and 10 of the part 5. The joints thus made are secured by the pressing of an X-shaped retainer 13 convex on one side and concave on

the other side, into each of the corners of 55 the screen sections 2 and 3.

The spring guide members 12 which engage the parts 4 and 6 of the opposite section, are tempered to impart springiness to the metal, and then turned part way back 60 to form a guide so shaped that the extreme end will alone bear against the opposite section and thereby insure the least possible friction in moving the sections. These spring guides 12 also hold the sections in 65 close contact and prevent insects from working between the sections.

Having thus described my invention what I claim is:

1. A window screen comprising sections 70 slidably secured together, each of said sections comprising a four piece frame and wire screen secured in said frame, the bottom and top pieces of said frame having portions cut to form spring guides adjacent 75 their ends, and means for securing the corners of said frames together.

2. A window screen comprising sections 80 slidably secured together, each of said sections comprising a four piece frame and wire screen secured in said frame, the bottom and top pieces of said frame having portions cut to form spring guides adjacent 85 their ends, the extreme ends of the free ends of said guides contacting with the top and bottom strips of the adjoining section.

3. In a window screen comprising sections, a metallic frame for said sections, said frame comprising four pieces bent upon themselves to form clamping faces for holding the wire screen, the top and bottom pieces of said frame having one of their said clamping faces cut at one end to form a lug the width of the side piece leaving a single thickness of metal, said single thickness of metal being inserted between the clamping faces of the adjacent side piece forming three sides of said frame, the opposite clamping face of said top and bottom pieces being clamped between the 90 clamping faces of the fourth side of said frame, and each of the corner joints of said frame having a portion pressed outward to 95 securely hold said joints from separation.

4. In a window screen comprising two 100 sections, a frame for each of said sections comprising four strips of metal bent upon themselves to form clamping strips to hold

the screen wire, each of the strips used for the top and bottom of said frame have one clamping face cut away adjacent one end and formed into a lug, said lug being bent at 5 right angles to the strip and then upwardly and inwardly forming a guide member, all of said clamping strips being so joined at the corners that one clamping face is disposed between the two clamping faces of the

adjacent strip and thus held in position, and 10 portions of the joints pressed outwardly to lock said joints.

In testimony whereof I hereto affix my signature in the presence of two witnesses.

JOHN ANTON FEIERABEND.
